UNITED STATES PATENT OFFICE.

ROBERT G. BULLARD, OF BIRMINGHAM, ALABAMA, ASSIGNOR OF TWO-THIRDS TO JOSEPH B. MOSLEY AND LAWRENCE H. BAKER, BOTH OF BIRMINGHAM, ALABAMA.

RAILROAD-TIE.

No. 927,324.

Specification of Letters Patent.

Patented July 6, 1908.

Application filed April 3, 1908. Serial No. 425,001.

To all whom it may concern:

Be it known that I, ROBERT G. BULLARD, a citizen of the United States, residing at Birmingham, in the county of Jefferson and State of Alabama, have invented new and useful Improvements in Railroad-Ties, of which the following is a specification.

This invention relates to railroad ties and more particularly to reinforced concrete ties.

10 The invention has for one of its objects to provide a cross-tie of simple, substantial and durable construction, and which is comparatively easy and inexpensive to manufacture.

15 A further object of the invention is to provide a simple and effective fastening device for attaching the rails to the cross-ties and for preventing the rails from spreading, the parts being so designed that the rails can be quickly and accurately laid and taken up 20 with facility, as in reconstructing the railroad track.

Another object of the invention is to provide a tie composed of two sections whereby the tie can be readily handled, each section 25 being provided with oppositely-extending arms disposed at such a point as to lie under the rails so as to afford supports therefor and thereby permit the ties to be laid at a greater distance apart than usual and at the same 30 time producing a strong and substantial foundation for the rails.

With these objects in view and others, as will appear as the description proceeds, the invention comprises the various novel features of construction and arrangement of parts which will be more fully described hereinafter and set forth with particularity in the 35 claims appended hereto.

In the accompanying drawing, which illustrates one of the embodiments of the invention, Figure 1 is a perspective view of a portion of a railroad track constructed in accordance with the invention. Fig. 2 is a longitudinal section of one of the cross-ties. Fig. 3 is a plan view of a cross-tie with the 45 rails fastened thereto. Fig. 4 is a section on line 4-4, Fig. 2. Fig. 5 is a perspective view of one of the fastening bolts.

Similar reference characters are employed 50 to designate corresponding parts throughout the several views.

Referring to the drawings, A designates the track rails which are of standard construction and laid upon ties B. These ties, 55 in the present instance, are molded of con-

crete or other suitable material and made in two sections 1 and 2. The sections are of any suitable size and are preferably reinforced by bars 3 of iron, said bars being spaced apart as shown clearly in Fig. 4 for 60 the purpose hereinafter to appear.

Extending vertically through each section is a bolt-receiving passage 4 disposed at the inner edge of the base of the rail, as shown in Fig. 2, and the reinforcing bars are spaced 65 apart at opposite sides of this passage for permitting the bolt 5 to pass between them. The head of the bolt, as shown in Fig. 5, is rectangular so that the bolt can be placed in the tie or removed therefrom after the tie has 70 been laid. The bolt is inserted in the passage 4 with the head 6 thereof lowermost and after it is fully inserted, the bolt is given a quarter turn so as to engage the ends of the head under the metal parts or reinforcing 75 bars 3, the shank of the bolt being of sufficient length to project from the top of the tie. The tie sections are preferably formed with oppositely-disposed arms 7 at points directly under the rails A whereby the rails 80 will be supported at all points. These cruciform tie sections are laid with the inner ends 8 together, and the top surface of each section has a depression 9 directly under the rails for receiving the extremities of the tie 85 bars 10. These tie bars are so designed as to prevent the rails from spreading and also to co-operate with the ballast of the roadbed to prevent the tie sections from spreading. The bar 10 is offset at 11 for engaging the 90 shoulders 12 or inner walls of the recesses 9, thereby effectively holding the tie sections in place, and the offsets provide shoulders 13 for receiving the fastening plates 14 that engage the bases of the rail sections at the inner 95 sides thereof. The plates 14 are apertured to receive the bolts 5 as are also the offset extremities 16 of the tie bar 10. The ends of the offset extremities are formed into base-engaging hooks 17 that hook over the bases 100 of the rails at the outsides thereof. These hooks co-act with the plates 14 to firmly hold the rails in position, and as the bar 10 is made in one piece, it serves the three-fold function of holding the tie sections 1 and 2 105 in contact with each other, to prevent the rail sections from spreading and to secure the rail sections to the ties.

The inner or meeting ends of the two sections are inclined oppositely from the top to 110

the bottom so as to permit the outer parts of the sections to be depressed under the weight of a train passing over the track, without undue strain or breakage of the bar 10, and at 5 the same time preventing the shoulders 12 from being destroyed. This provision also permits of the necessary vibration of the parts of the cross ties when a train passes over the track.

10 From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device 15 shown is merely illustrative and that such changes may be made when desired as are within the scope of the claims.

Having thus described the invention, what I claim is:—

25 1. A cross tie comprising cruciform sections made of concrete each having a vertical passage and a depression in the top surface into which the said passage opens, the inner and outer walls of the said depression forming shoulders, and a reinforcing device embedded in each section and provided with spaced members located at opposite sides of the passage, in combination with a tie bar extending from one section to the other of the 30 tie and provided with depressed ends seated in the depressions of said sections of the tie, and the extremities of the ends being bent upwardly and inwardly to form rail-engaging 35

hooks, rails extending over the depressed ends of the tie bar and having their bases engaged under the hooks, clamping plates arranged at the insides of the rails and engaging the bases thereof, shoulders on the tie bar with which the inner ends of the clamping plates engage, bolts in the passages of the 45 said sections and passing through apertures in the tie bar and clamping plates, each bolt having an elongated head shaped to pass between the members of the reinforcing device in positioning the bolt and also provided 50 with a non-circular portion adjacent the head for engaging between the said members of the reinforcing device to prevent turning of the bolt, and a nut on the upper end of each bolt for clamping the parts together. 55

2. A cross tie constructed of concrete and provided with vertical passages, metal reinforcing members therefor disposed transversely to and at opposite sides of the passages, bolts disposed in the passages and provided with elongated heads adapted to pass freely between the members in positioning or detaching the bolts and normally engaging under the members, the shanks of the bolts each having a non-circular portion adjacent 65 the head to engage between the members for preventing turning of the bolts when the latter are tightened, and rail-holding means secured in position by the bolts. 60

In testimony whereof I affix my signature 70 in presence of two witnesses.

ROBERT G. BULLARD.
